US0D1057714S

(12) United States Design Patent (10) Patent No.: US D1,057,714 S
(45) Date of Patent: * Jan. 14, 2025

(54) SMART RING

- (71) Applicant: Samsung Electronics Co., Ltd., Suwon-si (KR)
- (72) Inventors: Byungchan Lee, Suwon-si (KR); Jaehyung Hong, Suwon-si (KR)
- (73) Assignee: SAMSUNG ELECTRONICS CO., LTD., Gyeonggi-Do (KR)
- () Term: 15 Years
- (21) Appl. No.: 29/936,821
- (22) Filed: Apr. 10, 2024

(30) Foreign Application Priority Data

- Mar. 18, 2024 (KR) 30-2024-0010302
- (51) LOC (15) Cl. 14-02
- (52) U.S. Cl.
USPC D14/344; D24/167; D11/26
- (58) Field of Classification Search
USPC ..... D10/30, 31, 32, 38, 70; D11/1, 2, 3, 4, D11/5, 6, 26; D14/138 R, 344, 358; D24/167
CPC G06F 1/163; A44C 9/00; A44C 9/0053; A44C 5/00; A44C 5/02; A44C 5/022; A44C 5/025; A44C 5/0007; A44C 5/0015; A44C 5/0046; A44C 5/0053; A44C 5/2052; A44C 5/2071; G04G 17/00; G04G 17/08; G04G 17/083; G04G 17/045

(57) CLAIM

The ornamental design for a smart ring, as shown and described.

DESCRIPTION

FIG. 1 is a front perspective view of a smart ring showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is another front perspective view thereof.

The dot-dash broken lines in the figures represent a boundary of the claimed design and form no part of the claimed design. The remaining broken lines in the figures depict portions of a smart ring that form no part of the claimed design.

1 Claim, 6 Drawing Sheets
